Des. 405

Aaron Cook of Newtown, Conn.
Letters Patent No 405 Dated August 19th 1881.

The Schedule referred to in these Letters Patent and making part of the same,

To all whom it may concern:

Be it known, that I Aaron Cook, of Newtown, in the County of Fairfield, and State of Connnecticut, have invented or produced, a new and original design for the top of ladies hair combs, and I do hereby declare that the following is a full clear and exact description of the same reference being had to the annexed drawings, making a part of this specification in which.

Fig. 1. is a back view in elevation.

Fig. 2. is an end view, showing more particularly the form of the rings which compose the bead.

The Design consists of a bead placed on the top or upper part of the comb, said bead consisting of a series of oblique rings.

A, Fig. 1. represents the design which is a bead composed of rings a, said rings having an oblique position and the bead or series of rings a curved or bowed form precisely as shown in the drawing Fig. 1. The rings are about parallel to, - each other in their oblique position, and some distance apart there being spaces between them as represented.

What I claim as new and original and desire to secure by Letters Patent is -

The Design A, placed on the top or upper part of the comb formed or composed of the series of oblique rings as herein represented and described.
